(57) CLAIM

The ornamental design for a coffee mug with stirring apparatus, as shown and described.

DESCRIPTION

FIG. 1 is a side view in elevation of a coffee mug with stirring apparatus showing my new design, with the opposite side being a mirror image of the side shown, and includes a cup portion and a lid portion;

FIG. 2 is a plan view thereof;

FIG. 3 is a bottom view thereof;

FIG. 4 is a plan view thereof with the lid removed; and,

FIG. 5 is a side view similar to that of FIG. 1 but with a sidewall portion cut away to show interior construction.
